JOINT FOR DRIER FELT OF PAPER MACHINES

Michael J. Argy, Niagara Falls, N. Y., assignor to
 Argy Pre-Heating Corporation, a corporation of
 New York

Application September 11, 1930, Serial No. 481,329

6 Claims. (Cl. 24—205)

My invention relates to joints for the ends of drier felts of paper machines.

In a paper making machine employed for drying and processing wide sheets of paper one or 5 more heavy belts are used for carrying the sheets of paper over drying rolls and guiding them through the machine. These belts more commonly known as drier felts, are constructed of a very heavy canvas and recently a felt has been 10 used which is composed of interwoven layers of asbestos and cotton fabric. In order to make it possible to apply one of such wide belts or drier felts to the machine, it is necessary that the belt material be cut to the proper length and threaded around the rolls and a series of guide pulleys. 15 The ends are then brought together and secured by a suitable means ordinarily known as the seam. It is with this seam construction or rather the elimination of the usual seam that my invention is especially concerned.

Prior to my invention the most satisfactory and commonly used drier felt seam has been made by bringing the ends of the felt together and overlapping or doubling over the ends and 20 sewing them with a large hand needle or hand sewing machine after the felt is placed on the machine. A cover strip is then applied over the seam and sewed to the felt and it will be apparent that a thick bulge will result in the belt several inches wide. It has been difficult to obtain 25 a very smooth job with these hand sewed constructions and the bulge is objectionable because it will leave a mark on the paper. In addition, various other difficulties are present in the type 30 of seam commonly used. The several layers of heavy material at the seam become wet in use which often wets the paper near the finishing end of the machine causing it to be weakened which results in frequent breaks at the calender 35 stacks. When this thick seam once gets wet it is almost impossible to dry it out and such wet condition prevailing for a few weeks will soon cause the seam to decay and a failure occurs. A break in the seam will necessitate shutting 40 down the machine and repairing the seam if possible, and the ends of the felt are soon weakened requiring renewal of the entire felt. It has been necessary heretofore to renew these felts at intervals of from four to eight weeks.

45 In an attempt to avoid the objectionable features of the drier felt seams, an endless belt has been tried but the difficulty with an endless belt is that the large heavy rolls must be removed from the machine in order to apply the felt, and 50 since the felts have a relatively short life, it will

be seen that it is necessary to shut down the entire machine for a considerable time every few weeks to renew the felts.

Other methods have been tried to make a seam 5 that would not be bumpy, such as involving the use of copper rivets, clipper fasteners or special cements.

It is an object of my invention to provide an improved drier felt joint construction in which all of the disadvantages of the old drier felt seam 10 are eliminated.

Another object of my invention is to provide an improved felt joint construction in which the ends of the felts are held together by substantially continuous fastening means which can be 15 quickly closed in applying a new felt to the machine.

Another object is to provide an improved drier felt joint having fastening means for the ends of the drier felts which will provide for ventilation allowing steam to escape from the heated side of the felts through the fastening device.

Another object of my invention is to provide an improved drier felt joint which can be quickly applied and in which the ends are held together 25 by fastening means so proportioned and arranged as to avoid contact with the paper and thus eliminating breaking or marring the paper as by bulging felt seams.

Other objects and advantages of the invention 30 will occur to those skilled in the art upon reading the following specification in conjunction with the accompanying drawing, in which a preferred form and two slight modifications thereof are shown for purposes of illustration. In the 35 drawing:

Fig. 1 is a side elevation of a portion of a paper making machine shown more or less diagrammatically.

Fig. 2 is a detail view showing the manner in 40 which the ends of the felt are attached together after being placed on the paper making machine.

Fig. 3 is a cross-section through a portion of one of the rolls and drier felts illustrating my invention.

Fig. 4 is a plan view of a portion of the felt 45 showing my improved connecting means in conjunction therewith.

Fig. 5 is a cross-sectional view through the ends of the felt and fastening means.

Fig. 6 is a view similar to Fig. 4 showing a modification.

Fig. 7 is a cross-section similar to Fig. 5 showing another modification.

Fig. 8 is a section of belt showing insert which 55

is put in a new belt but taken out after it is stretched by wear and two ends of belt fastened.

In carrying out my invention a commonly known form of slide fastener is employed and has 5 proven particularly satisfactory in accomplishing the purposes of my invention.

A paper making machine as illustrated in Fig. 1 with which two drier felts constructed according to my invention are used, comprises a frame- 10 work of a suitable form such as indicated in broken lines at 11 which carries upper and lower series of bearings 12 and 13 respectively, and supports the steam heated rolls 14 of the upper series and 15 of the lower series and carrying rolls 16 15 of the upper series and 17 of the lower series, placed intermediate of the heated rolls. The strip of paper the thickness of which is here shown greatly exaggerated, may be guided to the large rolls in any suitable way such as by a small 20 or baby drier or carrying roll 18 and is fed over and under the heated drier rolls moving in a tortuous path as illustrated from the right hand end of the machine to the left hand end, where the paper is taken away from the rolls. Any number 25 of these rolls may be arranged in a series as desired and the width transversely of the machine, that is, the length of the rolls may be also varied to conform to the width of the entire machine, which usually is between one hundred and two 30 hundred inches, more or less. The strip of paper 19 is carried or directed alternately to the upper and lower series of drier rolls by the upper and lower drier felts, the upper and lower felts functioning independently of each other. The upper 35 felt is designated 20 and the lower felt is designated 21. These felts pass through the series of heated drier rolls and carrying rolls and then pass back over and under the machine, being guided on their return by suitable idler rolls or pulleys 40 designated as 22.

Referring to Fig. 3 each of the heated drier rolls or cylinders 14 and 15 has a hollow interior 23 to which steam under pressure is supplied by means of a suitable connection through one of the 45 bearings. It will be observed that the strip of paper is between the drier felts 20 and 21, and the drier rolls at all times when passing over and under the heated drier rolls. The felts thus hold the sheet of paper in contact with the heated 50 rolls over a considerable area which heats up the paper and dries it. The wide felts act as supports for the thin sheet of paper throughout its passage through the driers.

For the purpose of securing the juxtaposed ends 55 24 and 25 of each of the felts together, a fastening device 26 is used and it is not believed necessary to describe in detail, the construction and operation of such a fastener. For more detailed description, reference may be had to the patent to 60 Gideon Sundback No. 1,219,881, March 20, 1917. It is sufficient here to say that a fastener of this type comprises a pair of flexible fabric tapes 27 and 28 having cooperating series of fastener elements 29 attached to and projecting from their 65 adjacent edges, such fastener elements being adapted to be brought together and progressively engaged by means of a slider 30 which is conveniently actuated by a pull 31. The tape stringers 27 and 28 are securely attached to the ends 24 and 25 respectively of the drier felts by lines 70 of sewing indicated at 32. It is believed that the construction which will be preferred is the one shown in Fig. 5 where the fastener elements 29 are mounted on the single ply stringers 27 and 28, such stringers being mounted on what will be 75

called the outside surface of the felts with the fastener elements located just between the edges of the felt ends 24 and 25. It will be noted that the thickness of the drier felts is considerable and therefore, when the fastener is mounted in this manner, the metal elements 29 do not project below the inner surface and thus, never come in contact with the paper although there will be no objection if these elements contact with the intermediate rolls as they probably will do. However, after the felts are in use for some time, the metal elements will assume some such position as shown in Fig. 3. With this construction there is no seam or bulge or any projection whatever to leave a mark on the paper as in the previous construction, which my invention replaces.

In actual use, the fastener stringers with the interlocking fastener elements are attached to the ends of the drier felt preferably by the textile manufacturer who supplies the drier felts. It 20 is then an easy matter to apply the felts to the paper machine. They are passed over the heated and intermediate rolls and the guide pulleys and the ends 24 and 25 brought together. The proper ends of fastener elements 29 are then brought 25 together and threaded into the wide end of the slider 30; then the slider is pulled up to the end of the series and the drier felt is now fastened in position. Instead of leaving the slider 30 on the stringers as in the usual slide fastener, it is 30 preferably pulled completely off the stringers after they are interlocked in order to prevent any undue thickness of metal or bulge to cause a mark on the paper. It is necessary to connect the stringers or the ends of the drier felts together 35 at opposite ends of the series of fastener elements by a suitable semi-permanent connection one form of which may be a leather lacing 33 and 34 located at each end of the series of elements as shown in Fig. 4. This holds the fastener elements together at each end and thus prevents 40 their disengagement since they are of such nature that they must be engaged or disengaged progressively beginning at one end. It will be noted that the amount of work required to lace the felts 45 together at opposite ends is very small compared to the work of sewing the ends of the felts together across a belt as wide as one hundred and fifty inches.

If desired, the lacing at one end may be replaced by a suitable separating end connecting device applied to the stringers 27 and 28. As shown such a device may comprise a socket or eye member 35 attached to the stringer 27 and a suitable pin member 36 on the stringer 28. In use the pin member 36 is threaded through the slider and held in the eye of socket 35, and the pin is properly positioned by a stop 37 on the socket member. This form of connecting device 55 is more fully shown and described in a patent to 60 Elliot O. Seaver, No. 1,830,077, granted November 3, 1931.

In the modification shown in Fig. 7, the fastener elements 29 are mounted on two ply stringers 38 and 39, the plies of which may be positioned on opposite sides of the heavy canvas felts in order to equalize the tension and prevent any undue stresses. The metal elements 29 are thus located centrally but are not of such thickness as to contact with the paper.

One important feature of the invention resides in the fact that when the fastener is closed there remains a large number of small cracks or openings 40 as will be clear from Figs. 2, 4 and 6. By reason of these cracks or openings, the fastening 75

device acts as a traveling ventilator allowing considerable steam to escape from between the felt and the heated drier rolls. This is to be contrasted with the old form of seam which 5 trapped the moisture causing the ends of the felts to rot out and shorten its life in addition to causing considerable trouble due to wetting and weakening the paper at the ends of the driers.

One point to which particular attention should 10 be directed is that all felts stretch more or less and the usual custom has been to put the felt on with a temporary seam. After the stretch has all been jacked out, the jack is screwed back and the temporary seam is taken out then the slack 15 is taken up and a new seam sewed in. With my improved slide fastener seam an insert of the usual length of the slack can be inserted such insert being indicated at 41 in Fig. 8. After the usual stretch is all taken up the insert can be 20 removed and the fastener parts which remain on the ends of the felt can be brought together and interlocked. The use of the insert, of course, requires an extra complete fastener 42.

As a result of my invention it will be observed 25 that a new connection for the ends of drier felts has been provided which enables the felts to be put on the machine very quickly thus saving a large amount of the time heretofore required. This saving in time together with the fact that my 30 invention materially increases the life of the felts and practically eliminates all repair jobs on the felt seam, greatly reduces the time of shut-down of the machines and increases the output per machine. It will also be noted that by the use of 35 my invention, all difficulty due to marks being left on the paper is eliminated; thus producing a smooth and even product.

While I have in this application shown and 40 described by way of illustration, one preferred embodiment and some modifications thereof which my invention may assume in practice, it will be understood that the same are merely for purposes of illustration and that various other forms may occur to those skilled in the art.

45 What I claim as my invention is:

1. In a drier felt seam construction, a pair of 50 flexible fastener stringers secured to the meeting ends of the drier felt, cooperating series of fastener elements on the adjacent edges of said stringer, a slider embracing said elements for opening and closing the fastener said fastener elements adapted to be brought together and progressively engaged by the movement of said slider along said 55 series, and lacing at each end of said series of elements for holding the felt ends together at

such points and preventing disengagement of said fastener elements.

2. In a drier felt seam construction, a pair of 5 flexible fastener stringers secured to the meeting ends of the drier felt, cooperating series of fastener elements on the adjacent edges of said stringer, a slider embracing said elements for opening and closing the fastener said fastener elements adapted to be brought together and progressively engaged by the movement of said slider along said series, a separable end connection at 10 one end of said series of elements comprising inter-engageable parts connected to said stringers, and a semi-permanent connection for the ends of said stringers at the opposite end of said series. 15

3. A joint for the ends of drying felts of paper machines comprising a fastener consisting of a multiplicity of separable interlocking parts secured to the opposite ends of the felt, a member common to the respective parts and slidable 20 thereon to successively cause interlocking of the multiple parts and to move the ends of the felt into abutting relationship.

4. A joint for the ends of a drying felt of paper machines, said felt consisting of inner and outer 25 layers, a fastener consisting of a multiplicity of separable interlocking parts secured to the opposed ends of the inner layer, a member common to the parts and slidable thereon to successively move the respective parts into intimate interlocking engagement and to move the ends of the inner and outer layers into abutting relationship. 30

5. A joint for the ends of drier felts for paper machines comprising a slide fastener having co-operating sections attached to the opposed ends 35 of the felt on each section, a slider slidable on said sections for successively interlocking the parts and to move the ends of the felt into substantially abutting relationship, and other connecting means for said sections at each end of 40 said multiplicity of interlocking parts to prevent unintended opening of the same.

6. A joint for the ends of drier felts for paper machines comprising a slide fastener consisting of a multiplicity of interlocking parts secured 45 to the opposed ends of the felt, a slider slidable upon said parts for successively engaging the same, said parts when interlocked holding the ends of the felt in substantially abutting relationship, said interlocking parts affording a continuously fastened joint across the entire felt, 50 said interlocked parts having small spaces between them for escape of steam through the joint.
